UNITED STATES PATENT OFFICE.

JAY CEYLON STEESE, OF AKRON, OHIO.

SHADE-HOLDER.

1,045,628.

Specification of Letters Patent. Patented Nov. 26, 1912.

Application filed April 26, 1912. Serial No. 693,501.

To all whom it may concern:

Be it known that I, JAY CEYLON STEESE, a citizen of the United States, residing at Akron, in the county of Summit and State 5 of Ohio, have invented new and useful Improvements in Shade-Holders, of which the following is a specification.

This invention relates to a new and improved holder or supporting device for 10 shades, globes, reflectors, and similar articles, upon gas or electric lamps, the word "shade" being herein generically used to indicate generally all devices of this character.

The object of the invention is to provide 15 a lamp, either gas or electricity, with means for supporting and centering shades of the neckless variety, that is to say, where there is no curved neck on which mechanism of the ordinary type of supporter can engage. 20 Heretofore, this type of shade has been commonly provided with a metallic collar secured thereto and the mechanism for holding or supporting the shade engages the metallic collar, but the additional metallic 25 collar is a source of weakness and expense and hence, the object of this is, broadly, to provide means whereby a neckless shade or similar article may be detachably supported, and so held as to be permitted to expand and 30 contract under the changes of temperature without danger of fracturing the shade.

With the foregoing and other objects in view, the invention consists in the novel construction, combination and arrangement of 35 parts constituting the invention to be hereinafter specifically described and illustrated in the accompanying drawings which form a part hereof wherein is shown the preferred embodiment of the invention, but it is to be 40 understood that changes, variations and modifications can be resorted to which come within the scope of the claim hereunto appended.

In the drawings in which similar reference numerals indicate like parts in the different figures, Figure 1, is a view in side elevation of an inverted gas light to which is secured a neckless shade, the lamp being equipped with mechanism embodying one 45 form of my invention; and, Fig. 2, is an inverted plan view of the lamp equipped with the shade-holding mechanism shown in Fig. 1.

Referring to the drawings in detail the 50 reference numeral 1 denotes a lamp of ordinary and conventional type and here used to

illustrate the adaptability of my improved device for suspending or supporting a shade. Broadly, the idea of supporting the shade 2 is to provide a lamp frame with means which 50 may be passed through the small opening in the upper wall of the shade and which may then be expanded sufficiently to interlock behind the wall so as to thereby support the shade and at the same time center the same. 60 Substantially all lamp frames are provided with a depending flange 3 in which I cut openings 4 at suitable intervals, and the frame of the lamp is also customarily provided in its upper portion with one or more 65 openings 5. The preferred form of my invention, and which is here described, comprises a broken ring 6 of spring wire of a larger diameter when expanded than the opening 7 in the upper wall of the shade and 70 when contracted to be so reduced as to be easily inserted therethrough to permit the shade to be slipped thereover. In order to sustain the wire loop 6 I provide at one or 75 more points, say, by way of example, at 8 and 9, inturned portions forming fingers which are passed through the openings 4 which serve thereby to connect the spring ring 6 with the lower flange 3 of the lamp frame. The ends of the broken ring 6 are 80 inturned at 10 and are passed through a circumferential slot 11 in the flange 3 and afterward the ends of the wire are upwardly and outwardly bent at 12 and are provided with 85 bent portions or knobs 13 to be grasped by 90 the hands. When the lamp is constructed, as shown in the drawings, it will preferably have one of the ends 12 extending through each of the openings 5 and as the laterally-projecting portions 12 will rest on the wall 95 of the slot 11 it is thereby efficiently supported.

The shade is positioned by shifting the ends 13 of the resilient wire ring toward each other causing a contraction of the diameter of the ring sufficiently to permit the shade to be shifted upwardly until it engages the flange 3 after which the ends 13 are released allowing the ring to expand due to its inherent elasticity, causing the various 100 portions of the ring to engage the inner face of the upper wall of the shade around the opening 7, thereby securely holding the ring 105 adjustably in position, the ring serving as a resilient and yieldable support for the shade.

It will be obvious, of course, that other means may be employed which may give

panded or shifted laterally against the inner face of the upper wall of the shade, below the opening 7, but the device shown is the preferred construction.

5 It may be pointed out that this invention has no relation whatsoever to those forms of shade or globe provided with necks either straight or curved and pertains to the supporting only of the globes or shades which 10 are so unprovided.

I claim:

The combination with a lamp-frame provided with a depending annular flange at its lower end inwardly inclined in cross section, 15 providing an abutment, said flange provided with a plurality of radial openings arranged in spaced relation, the frame above said flange provided with an opening, a broken ring-shaped locking-member arranged to 20 normally spring outwardly, encircling said flange and having inwardly-extending ab-

ruptly-bent portions constituting radial projections arranged to engage in the radial openings in said flange for supporting said member, the ends of said member extending 25 upwardly and outwardly through the opening in said frame, with a neckless shade having an opening, arranged with the wall around said opening positioned against said flange as an abutment and held in position 30 against movement by said locking member when expanded to cause the latter to engage the under face of the shade around said opening.

In testimony whereof I have hereunto set 35 my hand in presence of two subscribing witnesses.

JAY CEYLON STEESE.
